UNITED STATES PATENT OFFICE

HENRY E. VAN NESS, OF ELMIRA, NEW YORK

DYEING APPARATUS

Original application filed March 11, 1926, Serial No. 93,821. Divided and this application filed October 27, 1926. Serial No. 144,413. Renewed November 9, 1929.

This invention relates to dyeing apparatus and more particularly to apparatus for carrying out the method of dyeing one or more predetermined parts of an absorbent mass, which is described and claimed in Patent No. 1,724,015, issued to Eclipse Textile Devices, Inc. on August 13, 1929. The present application is a division of my co-pending application filed March 11, 1926, Serial No. 93,821.

10 The object of the apparatus with which the present application is concerned is to facilitate carrying out the method of dyeing in which the dyeing liquid is passed rapidly through a predetermined limited part of a 15 wound mass of yarn, coloring this part of the yarn only; and more particularly to aid in carrying out a specific method of spot-dyeing yarn wound in the form customarily known as a cross-wound cone of yarn. This specific 20 method, which is described and claimed in my aforesaid co-pending application, is as follows:—

The cone is placed with the axis of its core 25 horizontal and is rapidly rotated about this axis. During the rotation, the liquid is poured on any desired zone of the inner surface of the core. The liquid reaches the inner surface of the mass through perforations provided in the core. The perforations need not 30 be limited to a particular zone of the core, but may be formed throughout the core, as the particular zone dyed is determined by pouring liquid on that zone only. The liquid is poured at such rate that the centrifugal force 35 causes it to penetrate into the mass immediately from the point at which it strikes the inner surface of the core. In consequence, the liquid cannot spread over the inner surface of the mass or the inner surface of the 40 perforated core, and so does not enter any part of the mass other than the zone lying radially outward from the point at which it 45 is poured on the inner surface of the core.

The supply of liquid to the inner surface 50 of the zone is then stopped, and the rotation is continued until no further liquid or mist is thrown off from the outer surface of the zone. This results in leaving the zone, which has been dyed, substantially dry, and thus eliminates all danger of subsequent coloring of other

parts of the mass by liquid soaking into them from the dyed zone.

While I have described this specific method as applied to a cone provided with a perforated core, it is also applicable to any wound mass from which the core has been removed so that the inner surface of the mass is directly exposed.

A convenient form of apparatus, embodying the present invention, and adapted to aid in carrying out the method described is illustrated in the accompanying drawings in which:—

Fig. 1 is an elevation in axial section; and

Fig. 2 is a similar view showing a modification of the apparatus shown in Fig. 1.

The apparatus illustrated comprises a rotary shaft 10' and a foraminous frusto-conical holder 15' secured to one end of the shaft. The shaft and holder are mounted with their axes horizontal. The cone of yarn C' to be dyed in this apparatus may have a core C' which is perforated throughout. The liquid is supplied to a predetermined zone of the inner surface of the mass through a pipe 25' which is mounted for adjustment lengthwise of the axis of the cone so that the liquid directed from its outlet 32 may be supplied to any desired zone of the inner surface of the mass. Such adjustment is effected by moving a receptacle 33 from which the pipe 25' extends along a rail 34 which is parallel to the axis of the cone. In using this device, the liquid is not supplied until after the rotation of the cone is started, and its flow is regulated by a valve 35 to such extent that the liquid striking the inner surface of the core C' is thrown directly into the mass by centrifugal force before it can flow along the inner surface of the core or the inner surface of the mass.

It is apparent that the apparatus shown in Fig. 1 may, if desired, be used in connection with a core having a set of perforations only at the zone to be dyed, and also that it may be used in connection with a mass containing no core.

If it is desired to dye more than one zone, the apparatus shown in Fig. 1 may be modi-

fied as indicated in Fig. 2 by providing a pipe 25² with more than one outlet.

What I claim is:

Apparatus for dyeing, comprising means 5 for rotating a mass of yarn containing a central opening, a pipe extending into the central opening of the mass and having a discharge nozzle, and means for adjusting said nozzle in a direction parallel to the axis of 10 the mass so that it will discharge liquid at any desired zone of the inner surface of the mass.

In testimony whereof I have hereunto set my hand.

HENRY E. VAN NESS.
